CLAIM

The ornamental design for a package, as shown and described.

DESCRIPTION

FIG. 1 is a perspective view of a package showing our new design;

FIG. 2 is a front view of the design shown in FIG. 1;

FIG. 3 is a rear view of the design shown in FIG. 1;

FIG. 4 is a left side view of the design shown in FIG. 1, the right side view being a mirror image thereof;

FIG. 5 is a top view of the design shown in FIG. 1;

FIG. 6 is a bottom view of the design shown in FIG. 1; and, FIG. 7 is a perspective view of a package showing our new design in a usage condition with an unclaimed decorative bow.

The broken line portion of FIG. 7 showing a decorative bow is included to show unclaimed subject matter only and forms no part of the claimed design.
